UNITED STATES PATENT OFFICE.

DUNCAN MORTON, OF VANCOUVER, BRITISH COLUMBIA, CANADA.

COMBINATION ENGINE AND PUMP STRUCTURE.

Application filed September 5, 1922. Serial No. 586,296.

To all whom it may concern:

Be it known that I, DUNCAN MORTON, a citizen of the Dominion of Canada, and resident of Vancouver, in the county of Vancouver and Province of British Columbia, Dominion of Canada, have invented certain new and useful Improvements in Combination Engine and Pump Structures, of which the following is a specification:

This invention has relation to certain new and useful improvements in combination engine and pump structures and has for its primary object the provision of a combination engine and pump structure which will be of simple and compact form as well as highly efficient in use and especially adapted to the forestry service where it is desirable to have structures of this character which may be readily transported as required without danger of disarrangement of the operative parts of the structure or other injury thereto which would interfere with proper operation of the mechanism.

The invention consists in the novel construction, combination and arrangement of cooperating elements as hereinafter more specifically set forth, claimed and shown in the accompanying drawings forming a part of the present application, in which:

Fig. 1 is a side elevation of the complete structure.

Fig. 2 is a plan view thereof.

Fig. 3 is an end elevation, looking at the pump end of the structure.

Fig. 4 is a vertical longitudinal section through the complete structure, with parts in elevation.

Fig. 5 is an enlarged end elevation of the pump with the end cover removed.

Fig. 6 is an enlarged section through the engine cylinder head, showing the intake and exhaust valves and also the water pocket of the engine cylinder head extending between the valves.

Referring more in detail to the drawings, in which similar reference characters designate corresponding parts throughout the several views, 10 designates the supporting base which is common to both the engine and pump, as shown in Figs. 1, 2 and 4. At one end, the supporting base 10 has an upstanding portion 11 formed to support the engine crank casing 12 having bearings 13 at its opposite sides for the main or crank

shaft 14, as shown clearly in Fig. 4. The bottom 15 of the engine crank casing 12 depends into the upstanding portion 11 of the supporting base 10 and bottom 15 has a further depressed portion 16 opposite the crank portion 17 of the main or crank shaft 14. This may also be clearly seen by referring to Fig. 1. A suitable drain cock 18 is secured in the lower portion of the engine crank casing 12 for draining the latter when desired. A gear wheel 19 is carried on the main or crank shaft 14 within the engine crank casing 12, the purpose of which will presently appear.

By referring to Fig. 1, it will be seen that the engine crank casing 12 is preferably constructed of upper and lower sections which cut through the bearings 13, the sections being suitably connected by clamping bolts 20. It will also be seen by referring to Fig. 4 that the engine crank casing 12 has an opening 21 in its upper side over which the engine cylinder 22 is mounted, said engine cylinder 22 carrying an out-turned flange 23 at its lower end, through which the bolts 24 are extended for clamping the engine cylinder 22 in position.

Mounted on an extended end of the main or crank shaft 14 is the balance wheel 25 with which is engaged a stop collar 26 located on the main or crank shaft 14, inwardly of the balance wheel 25. A suitable lock nut 27 is threaded on the outer extremity 28 of the main or crank shaft 14 to prevent the balance wheel 25 from working off of the main or crank shaft 14.

The engine piston 29 working within the engine cylinder 22 is mounted on the upper end of the piston rod 30 by suitable connection 31. The piston rod 30 has its lower end 32 suitably mounted on the crank portion 17 of the main or crank shaft 14, as shown in Fig. 4. It is to be understood that the engine piston 29 and the piston rod 30 are both of conventional form and therefore need no further detailed description.

The engine cylinder 22 has an annular flange 33 extending around the exterior thereof near the lower end of said engine cylinder 22. The sleeve 34 forming the water jacket for the engine cylinder 22 is positioned around the latter and in spaced relation thereto, the lower end of the sleeve 34 joining the annular flange 33. The sleeve

34 is of sufficient length to extend practically to the top of the engine cylinder 22, as shown in Fig. 4. The sleeve 34 has a water inlet opening 35 near its lower end, the purpose of which will presently be apparent.

The removable cylinder head 36 for the outer open end of the engine cylinder 22 is removably positioned on the upper end of the engine cylinder 22 and the water jacket 10 forming sleeve 34, as also shown in Fig. 4, with the central portion 37 of the removable cylinder head 36 depending into the engine cylinder 22. The removable cylinder head 36 is hollow, thereby providing the water 15 pocket 38 which also has communication with the water pocket 39 formed between the engine cylinder 22 and the water jacket forming sleeve 34 spaced around said engine cylinder 22. It will be understood that the 20 removable cylinder head 36 may be securely fastened in position in any suitable and well known manner.

The removable cylinder head 36 has a threaded water outlet port 40 at one side 25 for the water pocket 38, as shown in Fig. 4 and the purpose of which will presently appear. The removable cylinder head 36 also has a fuel inlet port 41 with an interiorly threaded outer end 42 while the valve 30 seat 43 is formed at the inner end of the fuel inlet port 41 for the inlet valve 44. The inlet valve 44 is mounted on the lower end of the valve stem 45 which reciprocates vertically through the removable cylinder head 35 36, as shown clearly in Fig. 6. A spring 46 is positioned around the outer or extended end of the valve stem 45 with one end of the spring bearing against the spring seat 47 formed on the upper face of the removable cylinder head 36. The other end of the spring 46 bears against the bearing washer 48 held in adjusted position on the upper end of the valve stem 45 by the adjustable nut 49 threaded thereon.

45 The exhaust port 50 is also formed in the removable cylinder head 36 with the outer end 51 of the exhaust port 50 interiorly threaded, while the valve seat 52 is formed at the inner end of the exhaust port 50. The 50 exhaust valve 53 normally engages the valve seat 52 and thereby closes the exhaust port 50. The valve stem 54 extends upwardly from the exhaust valve 53 and reciprocates through the removable cylinder head 36. The 55 expansion spring 55 is extended around the valve stem 54 with one end of the expansion spring 55 engaging the spring seat 56 formed on the outer face of the removable cylinder head 36, around the valve stem 54. The 60 other end of the expansion spring 55 bears against the bearing washer 57 mounted on the valve stem 54 and limited in its outward movement on the valve stem 54 by the stop pin 58 extended through the 65 valve stem 54.

It will be readily seen by referring to Fig. 6 that the water pocket 38 in the removable cylinder head 36 extends between the fuel inlet port 41 and the exhaust port 50. It will also be seen by referring to Figs. 70 1, 2 and 4 that a spark plug 59 of conventional form is mounted in a suitable opening 60 provided for this purpose in the removable cylinder head 36 and extending through the latter. The upper extremity 75 of the valve stem 54 for the exhaust valve 53 is suitably connected with one end of the exhaust valve operating rock arm 61, which latter is mounted intermediate its ends on the pivot member 62, the opposite or outer 80 end of the exhaust valve operating rock arm 61 being mounted on the pivot member 63, which latter also extends through the forked upper end 64 of the member 65 carried on the upper end of the reciprocating rod 66. 85 The outer end of the exhaust valve operating rock arm 61 is inclosed in the forked upper end 64 of the member 65, as will be clearly understood by referring to the drawings, particularly Figs. 1 to 4 inclusive. A 90 cotter pin 67 or the like is extended through one end of the pivot member 63 to retain the latter in position.

The reciprocating rod 66 extends through the upper portion of the bearing casing 68 95 and has its lower end 69 resting upon the cam member 70 on the cam shaft 71, which latter is rotatably mounted in the bearing casing 68 and corresponding bearing members 72 provided on the portion of the upper side of the engine crank casing 12 on which the bearing casing 68 is supported. A cushioning spring 73 is positioned around the reciprocating rod 66 with one end engaging with the bearing casing 68, while the upper end of the cushioning spring 73 engages the bearing washer 74 positioned on the reciprocating rod 66. Upward movement of the bearing washer 74 on the reciprocating rod 66 is prevented by the stop pin 75 extended through the reciprocating rod 66. The pivot member 62 is mounted in the upper end of the inclined supporting arms 76 of the plate 77 which is mounted on the upper face of the removable cylinder 115 head 36 near one edge thereof, by the bolts 78 or other suitable means. The bolts 78, together with similar and additional bolts 78 shown in Fig. 2, serve as the means to secure the removable cylinder head 36 in 120 position.

It will be evident that as the cam shaft 71 is rotated, the cam member 70 will, with each revolution of the cam shaft 71, force upwardly the reciprocating rod 66 and thereby operate the exhaust valve operating rock arm 61 to open the exhaust valve 53, against the action of the expansion spring 55. As the expansion spring 55 is permitted to operate to close the exhaust 130

valve 53 and return the exhaust valve operating rock arm 61 and the reciprocating rod 66 to normal position, the cushioning spring 73 serves to prevent sudden and unsteady movement of the operative parts mentioned and complete a gradual closing of the exhaust valve 53.

It will be clearly seen by referring to Fig. 4 that the cam shaft 71 carries a gear wheel 79 which meshes with the gear wheel 19 and thereby assures proper operation of the cam shaft 71 by the main or crank shaft 14. The gear wheel 79 is partially enclosed by the bearing casing 68, while the remainder of the gear wheel 79 projects into the engine crank casing 12.

Connected with the cam shaft 71 through the medium of the clutch 80, is the magneto shaft 81. The magneto 82, which is shown conventionally in the drawings, is supported on the supporting member 83 carried on the supporting base 10, about centrally of the pump supporting end of said supporting base 10. The supporting member 83 is secured to the upstanding flanges 84 of the pump supporting end of the supporting base 10 by bolts 85 or other suitable connecting members.

Tank supporting brackets 86 are mounted on the supporting base 10 at opposite sides of the pump supporting end thereof. The tank supporting brackets 86 are of substantially inverted U-shaped form and have long and short legs, the long legs being mounted on the bottom of the supporting base 10 near the corners thereof, while the short legs are mounted on the upstanding portion 11 of the supporting base 10, at the corners of the engine crank casing 12. The tank supporting brackets 86 have transverse bracing members 87 connecting the lower ends of the short legs with the long legs of said tank supporting brackets 86 and also have arcuate transverse bracing members 88 connecting the legs near the upper ends thereof.

The main portions of the upper ends of said tank supporting brackets 86 are of arcuate form and connect at their center portions with the uppermost central portions of the arcuate transverse bracing members 88, as shown at 89, these upper ends of the tank supporting brackets 86 thereby constituting lower arcuate supporting bearings 90 for the end portions of the fuel tank 91. Upper arcuate supporting bearings 92 are extended over the end portions of the fuel tank 91 and provided with out-turned ends 93 secured upon the upper ends of the tank supporting brackets 86 to either side of the lower arcuate supporting bearings 90, by suitable securing members 94, as shown clearly in Figs. 1 and 4. The fuel tank 91 has a filling opening normally closed by the plug 95 and a fuel supply pipe 96 extends

from the fuel tank 91 to supply fuel to the carburetor 123 connecting with the intake pipe 98 of the engine.

It will be understood that the intake pipe 98 is secured in the interiorly threaded outer end 42 of the fuel inlet port 41 in the removable cylinder head 36. It will also be apparent that the fuel passing through the fuel supply pipe 96 from the fuel tank 91 may be readily controlled by means of the valve 97 secured in said fuel supply pipe 96 near its point of connection with the fuel tank 91. It is also to be understood that suitable connections, not shown, are made between the spark plug 59 and the magneto 82 so as to assure proper operation of the spark plug 59 during operation of the engine. The engine exhaust pipe 99 projects from the exhaust port 50, as shown in Figs. 1 and 2, one end of the engine exhaust pipe 99 being secured in the threaded outer end 51 of said exhaust port 50.

The pump operating shaft 100 is in alignment with the main or crank shaft 14 and connected for operation with the latter by means of a clutch 101. The pump operating shaft 100 extends through the lower portion of the pump cylinder 102 and through the removable pump cylinder head 103 for the outer end of the pump cylinder 102. A suitable bushing and sleeve 104 is carried by the pump cylinder 102 and mounted around the pump operating shaft 100 to reduce leakage of the pump to the minimum. The pump cylinder 102 is mounted on the upstanding portion 105 of the supporting base 10, at the end opposite that end supporting the engine. This upstanding portion 105 is of proper size and shape to properly support the pump, as will be clearly apparent by referring to the drawings.

The removable pump cylinder head 103 is secured in position by the bolts 106 or other suitable means. A second pump shaft 107 is rotatably mounted in the upper portion of the pump cylinder 102 with one end of the second pump shaft 107 rotating in the bearing pocket 108 provided therefor in the closed head of the pump cylinder 102 and extended outwardly from the same. The opposite end of the second pump shaft 107 rotates in the bearing pocket 109 formed in the removable pump cylinder head 103 and pressed outwardly from the same. A corresponding bearing pocket 110 is also formed in the lower portion of the removable pump cylinder head 103 for the outer free extremity of the pump operating shaft 100. The pump cylinder 102 is provided with a water inlet pipe 111 located centrally at one side, while a similarly located water discharge pipe 112 projects from the upper side of the pump cylinder 102.

Mounted on the pump operating shaft 100 and the second pump shaft 107 are the

cylindrical rotatable pump members 113 and 114, respectively, which have spaced peripheral teeth 115 which are adapted to interlock at the center of the pump cylinder 102 and thereby cause rotation of the cylindrical rotatable pump members 113 and 114 in reversed directions as the pump operating shaft 100 rotates. Each of the cylindrical rotatable pump members 113 and 114 works 10 in a pocket just slightly larger than itself and the peripheral teeth 115 extend completely across the peripheral faces of the cylindrical rotatable pump members 113 and 114, thereby causing these peripheral teeth 15 115 to catch the water entering the pump cylinder 102 by way of the water inlet pipe 111 and carry the water around the cylindrical rotatable pump members 113 and 114 in the pockets between the peripheral teeth 20 115 thereof and discharge the water from the pump cylinder 102 by way of the water discharge pipe 112. This will be clearly understood by parties familiar with this type 25 of pump.

As the pump is operated with the engine, the water will be constantly discharged from the water discharge pipe 112. A portion of the water passing through the pump will also be forced through the water conducting pipe 116 into the water pocket 39. One end of the water conducting pipe 116 connects with the discharge side of the pump cylinder 102, while the other end connects with the water inlet opening 35 of 30 the water pocket 39. After the water has passed through the water pockets 39 and 38, it discharges by way of the water discharge pipe 117 projecting from the pipe connection 118 secured in the threaded water outlet 35 port 40, as will be understood by referring to Figs. 1, 2 and 4.

A conventional form of lubricant cup 119 is mounted on the removable cylinder head 36. The lubricant employed in the engine 45 crank casing 12 may be readily supplied thereto through the lubricant port 120 which is normally closed by the plug 121, as shown in Figs. 1, 2 and 3. An appropriate lubricant cup 122 is mounted on the pump 50 cylinder 102 for supplying the necessary lubricant to the pump parts. It will also be evident that any other appropriate means 55 may be employed for automatically lubricating other parts of the structure, as desired.

It is believed the complete construction and operation may now be readily understood from the foregoing paragraphs taken in connection with the accompanying drawings without further detailed description. It may be briefly stated, however, that the engine and pump are driven together by the main or crank shaft 14 and the pump operating shaft 100, arranged in alignment and 60 connected for operation together by the

clutch 101. Furthermore, a portion of the water forced through the pump cylinder 102 is employed for closing the engine cylinder 22 and the removable cylinder head 36 as the engine and pump operate, thereby increasing the efficiency of the structure or unit. The cam shaft 71 coupling with the magneto shaft 81 in alignment therewith and both shafts being controlled directly by the main or crank shaft 14, assures proper timing and operation of the exhaust valve 75 53 and the sparking or ignition mechanism of which the spark plug 59 forms a part.

What I claim as new is:

1. A structure comprising a supporting base having raised end portions; an engine crank casing mounted on one of said raised end portions; an engine cylinder mounted on and communicating with said engine crank casing; an engine crank shaft rotatably mounted in said engine crank casing; a piston mounted on said engine crank shaft and working in said engine cylinder; a removable hollow head for the outer end of said engine cylinder; a water jacket mounted around and spaced from said engine cylinder to form a water pocket around the same; said hollow removable head having a water pocket formed therein communicating with the first mentioned water pocket; a water conducting pipe connected with the lower portion of the first mentioned water pocket to supply water thereto; a water discharge pipe projecting from the hollow removable cylinder head to serve as an outlet for the second mentioned water pocket; said removable head for the cylinder having inlet and exhaust ports; inlet and exhaust valves carried by said removable head and normally enclosing the inlet and exhaust ports; said inlet and exhaust ports opening on opposite sides of the removable head; the water pocket of said removable head extending between the exhaust ports and around the same; a spark plug carried by said removable head; an exhaust valve opening mechanism; a cam shaft parallel with said engine crank shaft and driven by the latter; a cam carried by said cam shaft serving to operate the exhaust valve operating means; a magneto operative from said cam shaft; means for supporting the magneto above the supporting base; the shaft of the magneto being in alignment with and connected to the cam shaft by means of a drive clutch; a fuel tank for the engine; supporting brackets removably mounted on the supporting base at opposite sides thereof and serving as supports for end portions of the fuel tank; a fuel feed pipe extending from said fuel supply tank to the inlet port of the removable engine cylinder head; a carburetor carried on said fuel feed pipe; an exhaust pipe projecting from said outlet port of the removable engine cylinder head; 120 125 130

said spark plug being electrically connected with the magneto; and a balance wheel on said engine crank shaft.

2. A structure comprising a supporting base having raised end portions; an engine crank casing mounted on one of said raised end portions; an engine cylinder mounted on and communicating with said engine crank casing; an engine crank shaft rotatably mounted in said engine crank casing; a piston mounted on said engine crank shaft and working in said engine cylinder; a removable hollow head for the outer end of said engine cylinder; a water jacket mounted around and spaced from said engine cylinder to form a water pocket around the same; said hollow removable head having a water pocket formed therein communicating with the first mentioned water pocket; a water conducting pipe connected with the lower portion of the first mentioned water pocket to supply water thereto; a water discharge pipe projecting from the hollow removable cylinder head to serve as an outlet for the second mentioned water pocket; said removable head for the cylinder having inlet and exhaust ports; inlet and exhaust valves carried by said removable head and normally enclosing the inlet and exhaust ports; said inlet and exhaust ports opening on opposite sides of the re-

movable head; the water pocket of said removable head extending between the exhaust ports and around the same; a spark plug carried by said removable head; an exhaust valve opening mechanism; a cam shaft parallel with said engine crank shaft and driven by the latter; a cam carried by said cam shaft serving to operate the exhaust valve operating means; a magneto operative from said cam shaft; means for supporting the magneto above the supporting base between the engine structure and the pump structure; the shaft of the magneto being in alignment with and connected to the cam shaft by means of a drive clutch; a fuel tank for the engine; supporting brackets removably mounted on the supporting base at opposite sides thereof and serving as supports for end portions of the fuel tank; a fuel feed pipe extending from said fuel supply tank to the inlet port of the removable engine cylinder head; a carburetor carried on said fuel feed pipe; an exhaust pipe projecting from said outlet port of the removable engine cylinder head; said spark plug being electrically connected with the magneto; a balance wheel on said engine crank shaft.

In testimony whereof, I affix my signature.

DUNCAN MORTON.
